TREATMENT OF BENZENE HEXACHLORIDE

Percy W. Trotter, Baton Rouge, La., assignor to Ethyl Corporation, New York, N. Y., a corporation of Delaware

No Drawing. Application July 19, 1952,
Serial No. 299,926

4 Claims. (Cl. 260—648)

This invention relates to the treatment of an isomeric benzene hexachloride mixture to enhance the gamma isomer concentration therein and more particularly to a process for separating the gamma and delta isomers whereby the gamma isomer may be recovered from isomeric mixtures in high yields.

It is known that benzene hexachloride (1,2,3,4,5,6-hexachlorocyclohexane), hereinafter called BHC, occurs in a number of isomeric forms. For example, in the addition chlorination of benzene, at least five such isomers are formed having approximately the following weight distribution: alpha, 65 percent; beta, 8 percent; gamma, 13 percent; delta, 10 percent; and epsilon, less than one percent. It is also known that the gamma isomer is by far the most insecticidally active BHC isomer. Accordingly, it is desirable to concentrate isomer mixtures with respect to the gamma isomer to facilitate preparation of improved insecticidal formulations by the elimination of inert and odoriferous constituents thereof.

Prior methods have been disclosed for concentrating the gamma isomer in BHC isomeric mixtures by extraction and fractional crystallization from a solvent having different solubilities for the various isomers. The extraction is carried out using only sufficient solvent to dissolve the gamma isomer while leaving considerable quantities of the relatively insoluble alpha isomer undissolved. Separation of the undissolved alpha isomer can be accomplished by centrifugation, filtration or the like. The gamma isomer can be recovered, in part, from the more soluble delta and epsilon isomers by inducing supersaturation of the gamma isomer-containing extract and without inducing substantial supersaturation of the delta and epsilon isomers and concurrently forming a crystal crop high in gamma isomer. This induction of a state of super-saturation can be accomplished by concentration of the extract (removal of the solvent), temperature reduction (cooling the extract), addition of a solvent depressant (addition of water to methanol solvent, for example), or any combination of the above. In any event, however, the yield of relatively pure gamma isomer from BHC isomeric mixtures is limited by the delta isomer concentration in the extract. In other words, the degree of super-saturation induced in the extract determines the yield of the gamma isomer, but the degree of supersaturation induced must be limited so as to prevent crystallization of the delta isomer. Thus the gamma/delta solubility ratio at the crystallizing temperature in any solvent and the weight distribution of the isomers in the isomeric mixture determines the maximum yield obtainable in any known extraction and crystallization process. Using crude BHC, the optimum yield of gamma isomer is about 80 percent, not considering the loss in mechanical separation and the like. If the delta isomer is permitted to crystallize, it is extremely difficult to further purify the gamma isomer product by recrystallization.

In view of the above, it has been found necessary to discard considerable portions of the gamma isomer in the mother liquor from the crystallization operation, due

2

to its high concentration of delta isomer and other soluble constituents. This loss accounts for the major gamma loss in processes of this type. Up to the present, there is no suitable means for treating this high delta stream to recover its gamma content.

It is accordingly an object of this invention to provide a process for separating the gamma and delta benzene hexachloride isomers, thereby permitting the recovery of gamma isomer in high yields.

Another object of the invention is to provide a process of the above type, in which a relatively pure gamma isomer fraction may be obtained.

Another object of this invention is to provide a process of the above type which is adapted to economical large scale commercial operation.

Other objects and advantages of this invention will become apparent as the description proceeds.

It has now been found that BHC isomer mixtures containing relatively high concentrations of the delta isomer, relative to the gamma isomer (above one part of delta isomer to two parts of gamma isomer), can be separated when the BHC is in a state of partial fusion. Using this technique, a major portion of the gamma isomer previously lost can be recovered as a liquid fraction having a relatively low delta isomer concentration. It has further been found that this separation technique can be combined with any known extraction and crystallization processes so as to recover, in contrast with prior processes, essentially all of the gamma isomer normally lost in the high-delta-isomer crystallizer mother liquor.

The separation of the partially fused BHC is carried out without a solvent, although the presence of a small amount of solvent does not impair the process. The temperature of separation can be between about room temperature and 100° C. and is preferably carried out between about 30° and 85° C. Also, the separation can be carried out at a single temperature within the limits noted above. However, preferably the material being treated is gradually heated or heated step-wise from a temperature of about 30° to about 85° C. When a small amount of solvent is present, the temperatures are correspondingly lowered.

Although the theory of the above process is not entirely understood, it is believed that low melting point eutectic mixtures are formed between the various isomers. One of the lowest melting eutectic mixtures includes the delta and gamma isomer and is formed in a ratio of about two parts gamma isomer to one part delta isomer. Other slightly higher melting eutectic mixtures are also formed between the gamma isomer and other isomers. Eutectic mixtures having melting temperatures above about 100° C. have been found much less favorable to gamma isomer recovery. Thus, if the temperature of separation is raised materially above 100° C., these other eutectic mixtures are also recovered in the gamma-containing filtrate and, thus, essentially no concentration of the gamma isomer is obtained. In view of the above, it has been found preferred to begin the separation at about room temperature and gradually or periodically raise the temperature to between about 80°—100° C., while continuously separating and recovering the liquid phase.

The separation of the fused eutectic mixture can be effected by any suitable filter or separatory device. However, since efficient separation is desired, a centrifuge or the like is most preferred.

The present process for separating the delta and gamma isomer can be carried out in combination with any known extraction and crystallization process. Usually, after crystallization of a high-gamma fraction from an extract solution, the mother liquor from the crystallization is desolventized and the solute solids recovered. Such a fraction is a particularly suitable feed for the present

process. This mixture of isomers of BHC is maintained at or brought within the temperature range of operation, forming a fused or liquid phase. This phase is separated by any efficient liquid-solid separation unit operation. The liquefied phase so-obtained is substantially enriched in the valuable gamma isomer.

The filtrate obtained from this separation, if desired, is then further treated to concentrate the gamma isomer, either by a separate process or by recycling the filtrate to the extractor or to the crystallizer. If the alpha concentration in the centrifuge filtrate is relatively high, it is generally preferred to recycle the material to the extractor so as to eliminate excess quantities of this isomer in the high alpha extraction cake. If desired, however, the filtrate having excess alpha can be extracted by fresh solvent to eliminate the undesired alpha directly. When the alpha/gamma ratio is sufficiently low, the filtrate from the centrifugation or other separation means can be directly recycled to the crystallizer.

The feed for the above process may vary widely in isomer distribution but is particularly suited to high delta isomer feed stocks. Thus, this invention has a peculiar suitability for use in treating the high delta crystallizer mother liquor from prior extraction and crystallization processes. To best illustrate the advantages of the present process, the examples include a description of an overall process in which crude BHC is first extracted with methanol and a high gamma isomer fraction crystallized therefrom.

The following are typical examples of the present invention. All quantitative units are given in parts by weight.

EXAMPLE I

Crude BHC was extracted at 15° C. in a continuous process with methanol using a feed ratio of 1.8 parts of methanol to one part of BHC. The extract was concentrated by removal of 60 percent of the methanol. The concentrated extract was then crystallized at 15° C. and upon separation of the crystals, a portion of the mother liquor was recycled to the extractor. At steady state conditions, three-quarters of the mother liquor was recycled and one-quarter of the recycle was treated as follows: the methanol solvent was completely removed from the solids fraction of the mother liquor. The solids fraction comprised a BHC isomeric mixture (175 parts) having 36 percent delta isomer and 25 percent gamma isomer. This mixture was gradually heated over a two-hour period from 40° to 80° C. and the liquid fraction continuously recovered in a centrifuge. The filtrate so-obtained contained 72 percent of the solvent-free BHC and 34 percent gamma isomer, 18.5 percent delta isomer, 10.5 percent alpha isomer and the remaining primarily beta isomer and heptachlorocyclohexanes. The cake obtained in this centrifuge contained 2.8 percent gamma isomer and approximately 80 percent delta isomer.

EXAMPLE II

A BHC isomer mixture (135 parts) containing 36 percent delta isomer, 25 percent gamma isomer, 10.5 percent alpha isomer, and the remainder primarily beta isomer and heptachlorocyclohexanes, was centrifuged, using 750 gravities. The temperature during this centrifugation was gradually raised from 40° to 85° C. over a two-hour period. The filtrate (93.1 parts) had a gamma isomer purity of 32.8 percent corresponding to 91 percent yield. The filtrate also contained 21.7 percent of the delta isomer.

The important significance of the high gamma isomer recovery of this example, of course, is that the feed material in this embodiment represents, normally, a major "loss stream" in a process of extraction of crude BHC and crystallization of a high gamma fraction. By providing a recovery of the order of 90 percent of this

formerly discarded gamma fraction, the commercial merits of the process are obviously great.

EXAMPLE III

A BHC isomer mixture (105 parts) containing 36 percent delta isomer, 25 percent gamma isomer and 10.5 percent alpha isomer was centrifuged using 750 gravities. The centrifugation was started at 30° C. and the temperature was gradually raised to 130° C. over a two-hour period. The following table gives the results obtained for cuts at variations in temperature.

Table

Temperature ° C.	Filtrate (Parts)	Percent gamma in filtrate cut	Percent delta in filtrate cut	Percent of total gamma in filtrate cut	Percent of total delta in filtrate cut
22	Small				
30-40	23.9	29.0	17.6	25.4	11.1
40-50	21.3	27.5	19.1	22.3	10.8
50-60	12.4	34.5	23.8	16.3	7.8
60-73	12.5	40.0	28.6	19.0	9.5
73-85	3.5	36.0	35.5	4.8	3.3
85-130	6.5	4.2	82.0	0.6	14.1

This table shows that up to 85° C. approximately, 90 percent of the gamma isomer is recovered in the filtrate whereas only about 45 percent of the delta isomer is present therein. However, when the temperature is raised above 85° C. and particularly about 100° C., the undesired delta isomer recovery increases considerably whereas only small additional recoveries of gamma isomer are obtained.

It will be noted that the filtrate recovered up to at least 85° C. has a gamma/delta ratio essentially the same as the gamma/delta ratio in crude BHC and therefore essentially all of this filtrate may be treated, such as by crystallization, in a manner similar to crude BHC.

As is believed apparent from the foregoing, the present invention provides an economical and efficient method for separating the gamma and delta isomers of benzene hexachloride. This process is applicable to the treatment of essentially all isomer mixtures of benzene hexachloride. It is particularly useful, however, in treating mixtures having a high delta/gamma ratio. For this reason, the present process may be efficiently and conveniently used to treat the crystallizer mother liquor of prior known extraction and crystallization processes to recover the gamma isomer therefrom. As pointed out above, this crystallizer stream has been a total loss in prior processes and the present invention provides a means to recover at least 90 percent thereof as a valuable gamma isomer-containing material. While not limited thereto, the so-treated gamma isomer-containing material may be recycled to the process from which it was obtained. This means that in all processes which are limited by the concentration and solubility of the delta isomer, considerably increased yield of the gamma isomer can be obtained.

I claim:

1. A process for recovering the gamma isomer from an essentially solvent-free mixture of benzene hexachloride isomers, including the gamma, alpha and delta isomers, and having at least one part of delta isomer per two parts of gamma isomer comprising heating said mixture to a temperature within the range of from 30° to 100° C., separating the liquid phase formed while the mixture is within said temperature range from the solid phase, said liquid phase containing principally the alpha and gamma isomers and said solid phase containing principally the delta isomer.

2. In a process for recovering the gamma isomer from a crude benzene hexachloride isomeric mixture including extracting said mixture with sufficient solvent to dissolve essentially all of the gamma and delta isomers and leaving a substantial quantity of the alpha isomer undissolved, effecting crystallization of a part of the gamma isomer from the so-formed extract, and separating the gamma

isomer crystals from the remaining mother liquor solution, the improvement comprising recovering the dissolved benzene hexachloride containing gamma, alpha and delta isomers from said mother liquor solution, heating the latter essentially solvent-free benzene hexachloride to a temperature within the range of from 30° to 100° C., and separating the liquid phase formed within said temperature range from the solid phase, said liquid phase containing principally the gamma and alpha isomers and said solid phase containing principally the delta isomer. 10

3. A process in accordance with claim 1 wherein a liquid phase of said mixture formed at a temperature

between 30° C. and 85° C. is separated from the solid phase.

4. A process in accordance with claim 2 wherein said recovered liquid fraction is recycled to said crystallization step.
